Inventor

UNITED STATES PATENT OFFICE

JAMES P. KENNEDY, OF BROOKLYN, NEW YORK

RADIOCALENDAR

Application filed September 25, 1929. Serial No. 394,995.

This invention relates in general to so-called reminders by means of which recurring events may be scheduled so as to be called to mind as they occur.

5 One of the objects of this invention is the provision of a simple reminder or calendar on which events to occur at stated future intervals may be recorded so that they will not be overlooked.

10 Another object of this invention involves the construction of a simple device of this nature employing one card for each day in the week on which the events are recorded.

More particularly another purpose of this 15 invention is to construct a radio calendar on which may be recorded the various programs of the different stations which one desires not to overlook as they occur throughout the week.

20 Another object of the invention is the provision of a device of this nature which is particularly useful in recording events which occur on the same day and at the same time each week.

25 These and other objects as will appear from the following disclosure are secured by means of this invention.

This invention resides substantially in the combination, construction, arrangement and 30 relative location of parts all as will be described in greater detail hereafter.

Referring to the drawings

Figure 1 is a front elevational view of the device of this invention with the cards 35 extended;

Fig. 2 is a similar rear elevational view of the device;

Fig. 3 is a vertical cross-sectional view 40 through the device with all the cards in normal position.

It is quite frequently desirable to have some form of calendar or reminder on which may be recorded in an orderly fashion events which recur at regular intervals. This is 45 particularly desirable in connection with the use of a modern radio receiving set over which it is desired to listen in on certain programs which occur at the same time and on the same day of each succeeding week. A program 50 will be advertised to occur in the future and

it is almost necessary, in order not to overlook it, to have some form of reminder to call it to one's attention in time. The device of this invention while very simple meets these requirements. The device is also arranged to 55 recall not only regularly recurring events, but special events or programs which have been advertised to occur in the future. This invention is particularly described in connection with the recording of radio programs, but it will be apparent after description of the device that it is not limited to this field of recording.

Referring to the drawings for a better 60 understanding of the invention the device is shown as comprising seven cards indicated by the numerals 1, 2, 3, 4, 5, 6 and 7, one for each day in the week. These cards are of such size and shape that they will fit easily into a container 8 made of any suitable stiff 65 material having the opening or window 9 on one side thereof and the opening or window 10 on the other side thereof, while one of the features of the invention involves the manner of marking the cards so that the faces of the 70 cards which appear in both windows are for recording events on the same day. Thus the card for Sunday when in the folder is exposed through the window 9 so that the events 75 may be recorded thereon. With the other cards arranged in their proper order as shown in Figure 1 the card in the folder with its face appearing through the back window 10 will also be exposed for recording the Sunday 80 events. This is secured by marking the back 85 of the Sunday card No. 7 for Monday records, the back of the Monday card No. 6 for Tuesday records, the back of the Tuesday card No. 5 for Wednesday records, the back 90 of the Wednesday card No. 4 for Thursday records, the back of the Thursday Card No. 3 for Friday records, the back of the Friday card No. 2 for Saturday records, and the back 95 of the Saturday card No. 1 for Sunday records. Thus each day as the front card is removed and placed at the rear of the cards the records for that day will be exposed in both the front and back windows of the folder.

The cards have been shown marked ar- 100

ranged in a suitable manner for recording radio program events, but it is to be understood that it can, of course, be marked to record other events. Thus the front of each 5 card is provided at the top with a symbol indicating the day. It is ruled with five columns and spaced off horizontally. The central column is for recording the exact time of a recurrence of the event. The two columns on either side of the central column are 10 for recording the designating station symbol, and the two outer columns are for recording the name of the event. These columns are designated by symbols on the top of the container as follows: "Time" "Station" and 15 "Program" respectively. To the left at the top is placed the symbol "A. M." and to the right of the top is placed the symbol "P. M." both on the container. On the rear of each 20 card which is also given a symbol to indicate the day are provided three vertical columns horizontally ruled. These three columns are designated by symbols on the container as follows: "Time" "Station" and "Program". 25 The lower portion of the card under the symbol "Special, not weekly" is marked off in four vertical columns, also horizontally ruled. These columns are designated respectively by the symbols "Date" "Time" "Station" and "Program". A suitable symbol is 30 provided at the top of the folder on the back such as "Afternoon" and "Special". The hours from noon to 5 p. m. are provided on the back of the cards in the manner shown 35 because it is not usual to listen to programs from midnight to 5 a. m., while the markings on the front of the device take care of one column of time symbols both A. M. and P. M. programs. It is, of course, to be understood 40 that all of the cards are wholly within the container as shown in Fig. 3, and have only one shown extended in Figs. 1 and 2 to give a complete disclosure of the device. With 45 each card marked on the front and back as indicated as the cards are withdrawn each day and moved to the back the proper card is exposed both front and back for the day.

It will be apparent from the foregoing disclosure that I have devised an exceedingly 50 simple and yet efficient device involving certain principles of construction and association which may be embodied in other physical forms without departing from the spirit and scope of this invention. I do not, 55 therefore, desire to be strictly limited to the disclosure as given for purposes of illustration, but rather to these principles as defined in the appended claims.

What I seek to secure by United States 60 Letters Patent is:

1. In a calendar device as described, the 65 combination comprising a container having an opening in the front and rear thereof, seven cards in said container one for each day 70 in the week, and designated spaces on said

cards arranged so that the face of the card exposed through the front window and the face of the card exposed in the rear window are both for the same day.

2. In a calendar device of the type described, the combination with a receptacle 75 having a window on two sides thereof, of a plurality of cards having the indicia Sunday, Monday, Tuesday, Wednesday, Thursday, Friday and Saturday on one face thereof and the indicia Monday, Tuesday, Wednesday, Thursday, Friday, Saturday and Sunday on 80 the other face thereof respectively, so that with the cards in the above named order in the folder the faces of the cards exposed in both windows will be for the same day.

3. In a calendar device of the type described, the combination with a receptacle having a window on two sides thereof, of a plurality of cards having the indicia Sunday, 85 Monday, Tuesday, Wednesday, Thursday, Friday and Saturday on one face thereof and the indicia Monday, Tuesday, Wednesday, Thursday, Friday, Saturday and Sunday on the other face thereof respectively, so that with the cards in the above named order in the folder the faces of the cards exposed in both windows will be for the same day, and designated spaces on both faces of each card for recording thereon data pertaining to the 90 day represented by these faces.

4. In a calendar device of the type described, the combination comprising a container having an aperture in two sides thereof, seven cards in said container one for each 100 day in the week, indicia on each card for indicating the day of use therefor, and designated spaces on each face of each card for recording therein predetermined data.

5. In a calendar device of the type described, the combination comprising an open-ended container having co-extensive apertures in two faces thereof and a plurality of cards in said container having the exposed 105 face of the two outer cards appearing through the apertures, and symbols on the front and back of each of said cards so that the faces of the exposed cards are for the same period of time.

6. In a calendar device of the type described, the combination comprising an open-ended container having co-extensive apertures in two faces thereof and a plurality of cards in said container having the exposed 110 face of the two outer cards appearing through the apertures, symbols on the front and back of each of said cards so that the faces of the exposed cards are for the same period of time, and a plurality of designated spaces on each 115 face of each card for recording predetermined data thereon.

In testimony whereof I have hereunto set my hand on this 24th day of September, A. D. 1929.

JAMES P. KENNEDY.
